POLISHED ROD ROTATOR

Filed June 29, 1926

2 Sheets-Sheet 2

UNITED STATES PATENT OFFICE.

ALEXANDER BOYNTON, OF SAN ANTONIO, TEXAS.

POLISHED-ROD ROTATOR.

Application filed June 29, 1926. Serial No. 119,509.

This invention relates to rotors of the positively actuated type, especially adapted for use in intermittently turning the polished rod and other reciprocating equipment 5 of a pumping well.

Briefly stated, an important object of this invention is to provide a polished rod rotor which may be economically and expeditiously installed on a pumping well to impart 10 an intermittent clock wise rotation to the rods to avoid parting of the rods at one or more joints thereof, and to avoid the formation of squirt grooves in the working barrel and the plunger or cups reciprocating 15 therein, all of which overcomes cutting of the oil and the necessity for frequently pulling the rods etc.

A further and equally important object 20 of the invention is to provide a positively actuated rotor comprising novel means by which the rotor is rendered temporarily inoperative should the cups or plunger become stuck in the working barrel whereby twisting of the rods to the breaking point is prevented.

Other objects and advantages will be apparent during the course of the following description.

In the accompanying drawing forming a 30 part of this application and in which like numerals are employed to designate like parts throughout the same,

Figure 1 is a side elevation of the improved rotor applied;

Figure 2 is a front elevation of the improved rotor applied;

Figure 3 is a perspective of a saddle embodied in the invention;

Figure 4 is a detail sectional view illustrating a slight modification of the invention applied.

In the drawing, the numeral 5 designates the beam of a pumping jack while the numeral 6 designates a polished rod trunnion 45 through which a polished rod 7 is extended in the usual and well known manner.

The invention contemplates the employment of what might be said to be a U-shaped saddle 8 having a centrally arranged opening to receive the polished rod and having sides recessed at the lower ends thereof, for partially receiving the lateral branches of the trunnion 6 as clearly shown in Figures 1 and 2. The walls of the recesses in the 55 lower terminals of the saddle are provided with shallow notches 9 to receive burrs

which may be on the lateral branches of the trunnions. It might be added that such burrs are frequently present on the lateral branches of the trunnion as a result of parting of the molders' pattern. The provision of the shallow recesses 9 also enables the curved walls of the recesses at the lower ends of the saddle to have a better contact with the trunnion to avoid lost motion. 60 That is to say, the presence of the shallow recesses 9 permits of the desired limited rocking of the saddle on the trunnion as a result of the conversion of the rocking of the beam into the reciprocation of the rods. 70

The saddle is provided in the top thereof, with a shallow recess 10 freely receiving the lower portion of the hub of a ratchet wheel 11. Sufficient clearance is left between the hub and the side wall of the recess 10 to freely receive a suitable lubricant which may be introduced with the aid of a squirt can or otherwise. 75

In carrying out the invention, the hub of the ratchet wheel 11 is extended above the 80 ratchet wheel and is provided with a plurality of set screws 12 adapted to engage the polished rod to positively lock the ratchet wheel to the rod. Therefore, intermittent rotation of the ratchet wheel will 85 result in similar rotation of the polished rod. A polished rod clamp 14 of conventional or other design may be connected to the polished rod immediately above the ratchet wheel to transmit the load of the polished 90 rod to the ratchet wheel and from the ratchet wheel to the saddle 8. At this point, it is noted that preparatory to and during the application of the polished rod clamp 14, the original polished rod screw of the 95 trunnion is allowed to remain tight. However, after the clamp has been properly applied, the original screw of the polished rod is loosened to allow of the free intermittent turning of the polished rod under the influence of the rotor. 100

Figure 2 clearly illustrates that the saddle 8 is provided with a laterally projecting suitably braced stub shaft 18 upon which the hub 20 of a crank arm 21 is mounted 105 for the limited rocking necessary for the successful operation of the device. The upper portion of the crank 21 is provided with a bearing receiving a pivot bolt 22 upon which a pawl 24 is loosely mounted. 110

The pawl 24 is in turn engaged with the radial teeth on the upper surface of the

ratchet wheel so that when the crank 21 is rocked in a counter clock wise direction the ratchet wheel and the rods will be turned in a clock wise direction to exert a tightening force on the rods at the joints thereof, and to turn the cups or plunger, as the case may be, in the working barrel whereby to avoid the formation of squirt grooves or jets in the working barrel and the reciprocating equipment therein, be it cups or a plunger. As previously stated, by thus avoiding the formation of grooves in the working barrel and the cups therein, cutting of the oil is avoided and the necessity for frequent pulling of the rods is overcome. Furthermore, the efficiency of the pump is substantially increased as each stroke of the pump will result in maximum production, provided of course, other factors do not interfere.

20 Before proceeding with the description of the operating means for the crank 21, it is desired to emphasize the important fact that should the cups or the plunger become stuck in the working barrel the rotor will not twist the rods to the breaking point. Assuming the cups are stuck firmly in the working barrel the rotor will continue to turn the rods until sufficient back strain has been built up to turn the ratchet wheel in a counter clock wise direction on the return movement of the pawl 24. It is important to observe that in the normal operation of the rotor, the hub of the ratchet wheel turns in a clock wise direction in the recess 10 when actuated by the pawl 24 and the weight of the rods on the hub of the ratchet wheel will cause the ratchet wheel to remain in a fixed position during the return or back stroke of the pawl 24. However, if the cups are stuck, sufficient back twist will be built up in the sucker rods to turn the ratchet wheel back during the return of the ratchet 24 notwithstanding the friction between the lower end of the hub and the bottom wall of the recess 10. The moment the cups are freed the rotor will again function normally and impart the desired intermittent rotation to the rods, a feature of major importance.

25 The bearing 20 is provided with a sprocket wheel 26 about which the intermediate portion of a sprocket chain 27 is trained. One end of the chain 27 is, as illustrated in Figure 1, connected to an anchoring clip 28 through the medium of a tensioning spring 29. The other end of the chain is trained about and is therefore anchored to a sprocket wheel 30. The sprocket wheel is in turn non-rotatably and adjustably connected to an attaching arm 31 through the medium of a nut and bolt 32. If desired the anchoring device 28 may also be in the nature of a sprocket wheel.

30 Figure 1 clearly illustrates that the bolt 32 is extended through a slot 33 in the arm 31 and that the bolt may be easily adjusted

in the slot so that the effective movement of the chain may be varied, this feature providing a means whereby the effective movement of the pawl 24 may be regulated. Of course, it is preferable to have the anchored parts of the chain approximately equal distances in front and in back of the polished rod as suggested in Figure 1. This figure clearly shows that the clip 28 is mounted on a bolt 35 adjustable in a slot 36 similar to the slot 33 so that both the clip 28 and the wheel 30 may be easily adjusted. The outer terminals of the slots 33 and 36 may be enlarged to allow of the passage of the heads of the bolts 32 and 35 during the application or removal of the same.

35 Further reference to Figure 1 will show that the sprocket wheel 30 may be adjusted about the axis of the attaching bolt 32 and the bolt subsequently tightened to positively hold the ratchet wheel 30 against turning. The coil spring 29 provides a simple means whereby the chain may be tensioned.

40 The arm 31 is attached to the beam at one side thereof by an attaching plate 40, the ends 41 of which are extended about some of the flanges of the beam 5 and are firmly anchored in place by means of a set screw 42. A wedge 43 may be employed between one of the ends 41 of the base 40 and the adjacent flange of the beam.

45 In the form of invention illustrated in Figure 4, the relatively fixed member 50 corresponding to the saddle 8 may be in the nature of a hollow cylinder having set screws 51 which may be engaged with the upper portion of the trunnion whereby to lock the member 50 to the trunnion. In this case the upper portion of the saddle 50 may be recessed to receive the upper portion of the hub of the ratchet wheel, all of which is clearly shown.

50 Having thus described the invention, what is claimed is:

1. A polished rod rotor comprising a ratchet wheel having a hub provided with means whereby the same may be locked to a polished rod, a crank having a pawl engaged with said ratchet wheel, a sprocket wheel having connection with said crank, and a chain trained about said sprocket wheel for rocking the same.

2. A polished rod rotor comprising a ratchet wheel having a hub provided with means whereby the same may be locked to a polished rod, a crank having a pawl engaged with said ratchet wheel, a sprocket wheel having connection with said crank, a chain trained about said sprocket wheel for rocking the same, and an anchoring device for connecting the ends of the chain to the beam of a pumping jack.

3. A polished rod rotor comprising a ratchet wheel having a hub provided with means whereby the same may be locked to a

polished rod, a crank having a pawl engaged with said ratchet wheel, a sprocket wheel having connection with said crank, a chain trained about said sprocket wheel for rocking the same, and an anchoring device for connecting the ends of the chain to the beam of a pumping jack, there being means whereby excessive back twist in the sucker rods of a well pump may be relieved.

10 4. A polished rod rotor comprising a saddle having means whereby the same may be rigidly mounted on a polished rod trunnion, a crank arm rotatably connected to the saddle and having a pawl, a ratchet wheel engaged by said pawl and having a hub provided with means whereby the same may be locked to a polished rod, a power transmitting member connected to the crank to rock the same, and means whereby the 20 power transmitting member may be attached to a jack beam, the hub of said ratchet wheel being mounted on the saddle to transmit the weight of the polished rod to the saddle.

25 5. A polished rod rotor comprising a ratchet wheel having means whereby the same may be attached to a polished rod, a saddle supporting the hub, a crank provided with a pawl engaging the ratchet wheel, a sprocket wheel connected to the crank, a 30 sprocket chain having the intermediate portion thereof, trained about the wheel, an arm adapted for connection to a jack beam, and anchoring devices having means whereby the same may be adjusted on the arm, said chain being connected to said anchoring devices.

35 6. A polished rod rotor comprising a ratchet wheel having means whereby the same may be attached to a polished rod, a saddle supporting the hub, a crank having

connection with the saddle and provided 40 with a pawl engaging the ratchet wheel, a sprocket wheel connected to the crank, a sprocket chain having the intermediate portion thereof, trained about the wheel, an arm adapted for connection to a jack beam, 45 anchoring devices having means whereby the same may be adjusted on the arm, the ends of said chain being connected to said anchoring devices, and tensioning means for said chain. 50

7. A polished rod rotor comprising a driven member having means whereby the same may be connected to a polished rod, a sprocket wheel having connection with said driven member, a chain trained about said 55 wheel, a second sprocket wheel having connection with said chain and constituting an attaching means for one end of the same, a second attaching means for the other end of the chain, and an arm supporting said 60 first and second named attaching means and adapted for connection with a jack beam.

8. A polished rod rotor comprising a driven member having means whereby the same may be connected to a polished rod, a 65 sprocket wheel having connection with said driven member, a chain trained about said wheel, a second sprocket wheel having connection with said chain and constituting an attaching means for one end of the same, a 70 second attaching means for the other end of the chain, and an arm supporting said first and second named attaching means, said attaching means being adjustable on said 75 arm to vary the effective movement of the chain.

In testimony whereof I affix my signature.

ALEXANDER BOYNTON.
